UNITED STATES PATENT OFFICE

2,596,976

POST STRAIGHTENING JACK

Edford E. Barber, New Haven, Conn.

Application October 17, 1946, Serial No. 703,892

1 Claim. (Cl. 153—48)

1

The present invention relates to new and useful improvements in devices for straightening the posts of parking meters and similar posts imbedded in concrete without requiring removal of the posts.

The posts provided for supporting parking meters frequently become bent by vehicles coming into contact therewith and usually it is the practice of removing the posts from the concrete in order to straighten the same and which requires considerable time and labor, since the post is imbedded in concrete.

Accordingly, it is an object of the present invention to provide a post straightening jack by means of which the post may be straightened without necessitating removal thereof from the concrete.

A further object of the invention is to provide a device of this character which may be easily and quickly anchored in position adjacent the base of the post for supporting a jack in an inclined position to exert pressure against the post in a direction to straighten the same.

Another object is to provide a portable post straightening device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view.

Figure 2 is a side elevational view.

Figure 3 is a sectional view taken on the line 3—3 of Figure 1.

Figure 4 is a top plan view illustrating the use of a hook for connecting the base of the device to a post.

Figure 5 is a side elevational view thereof, and

Figure 6 is a perspective view of a modified anchoring attachment for the device.

Referring now to the drawings in detail wherein for the purpose of illustration I have disclosed a preferred embodiment of the invention the numeral 5 designates a U-shaped angle iron member providing an elongated supporting base at the open end of which is welded or otherwise secured a cross-plate 6 through which a vertical adjusting screw 7 is threaded, the screw having a base 8 secured at its lower end and provided at its upper end with transversely extending and manipulating handles 9.

The base 8 of the adjusting screw 7 is placed on the surface of a street 10 with the closed end of the base 5 resting on the curbing 11 and embracing a post 12 adjacent its lower portion, the

lower end of the post being imbedded in the sidewalk 13 and employed for supporting a parking meter (not shown) on the upper end thereof.

In order to straighten the posts which have been bent outwardly toward the curbing as shown by the dotted lines in Figure 2 of the drawings a sectional clamping collar 14 is secured to the upper portion of the post by a bolt or nut 15, the collar being formed with a lug 16 projecting from one side thereof.

The numeral 17 designates a conventional form of jack which may comprise a hydraulic or pneumatic jack, or other type of manually or power operated jack and which in the present instance, includes a cylinder 18 having a plunger 19 working therein and with a head 20 at the upper end of the plunger engaging the lug 16.

The jack base 21 is removably positioned in a tray-like member 22 positioned between a pair of upright plates 23 welded or otherwise suitably secured to the sides of the base 5 adjacent the outer end of the latter. The tray 22 is provided with extension plates 24 at the sides thereof positioned between the upright plates 23 and pivotally attached thereto by means of a transverse pin 25 for vertical swinging movement of the jack.

The jack also includes a manipulating handle 26 for manual operation of the plunger 19 by a forward and backward movement of the handle.

In the operation of the device, the base 5 supported at one end on the screw 7 and with its other end embracing the lower portion of the post 12, the jack 17 is tilted in a position to engage the lug 16 adjacent the upper bent end of the post whereupon through the operation of the jack pressure will be exerted on the post to straighten the same into the position as shown by the full lines in Figure 2.

Where it is desired to position the lower end of the jack further away from the post a transverse pin 27 is placed transversely of the base 5 adjacent its inner end and to which one end of a hook 28 is secured with the hook projecting forwardly of the base 5 to engage the lower portion of the post 12.

Also, if desired, a U-shaped anchoring member 29 may be interchangeably connected to the pin 27 for engaging the post 12 in place of the hook 28.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same

is susceptible to certain changes fully comprehended by the spirit of the invention as herein described and the scope of the appended claim.

I claim:

In a post straightening device, a U-shaped ground engaging base member adapted to straddle the post with the bight end of said base member engaged with the post, a cross member connecting the ends of said base member and having a ground engaging jack screw threaded therethrough for levelling said base member on the ground, a clamp attachable to the post above said base member and provided with a lateral lug, and a fluid pressure jack having a base end pivotally supported on said base member for swinging of said jack into differently upwardly inclined positions, said jack including a plunger having a head removably positionable at will under said lug for upward pressure against said lug diagonally of said post.

EDFORD E. BARBER.
